Davis barrel

Letters, Patents.

The schedule referred to in these Letters Patents and making part of the same containing a description in the words of the said Davis barrel, himself, of his "Improvement in the Machine for Churning Butter."

It is to whom these presents shall come: Be it known that Davis barrel of Illinois in the County of Kankakee and State of Illinois, have invented a new and useful improvement in a machine for churning butter from milk and cream and that the following is full and exact description thereof. I make a box eighteen inches high, two inches square at the top and six by sixteen at the bottom. The box is halved together at the corners and a concave plank bottom part is in the same manner encinched and along that a rabbit is made on the inside at the top of the box, which goes towards and three eighths deep so as to admit the cover. The cover is put on in three pieces so as to leave a space between the middle and the two outside ends six inches wide and exceeding quite a ways for the churning work. These spaces are left half way from the center of the front piece inside edge each way. They make a bench like feet four inches long and sixteen inches wide standing upon legs sixteen inches high from the floor to the top of the bench and one inch and a half square. The end of this bench is with a square hole of sufficient size to admit the top of the box of a size enough to let the legs rest on the floor. Each side of this hole in the edge of the bench and in the centre of the side of the box opposite each other are set two posts perpendicular to the top of the box high and four inches wide at the bottom.

iron at the top and one nail a half inch in thickness. Along the top of these posts or through them is put a pin three fourths of an inch in diameter so as to reach through them both. Then make two breakers paddles long enough to reach from the pin to the bottom of the box on each side of the lower end of these breaks below the corner of the box are set with pins four inches long and one inch wide and three fourths of an inch thick; and are set as follows: i. is found necessary to produce sufficient friction to oppose the pull from the eccentric. Through the top of these breakers is left a hole three fourths of an inch in diameter, through them in the box through the spaces in the corner and post through the holes in the top of the breakers the before mentioned pin, leaving the breakers at liberty to pass before and aft free from the bottom of the box. ^{the eccentric} from corner to corner from the centre of the box and opposite each other. I put two posts in which I place a double iron crank long enough to extend to project over the side of the box where the handle is put on. The eccentric of the crank is to revolve opposite each other; from each extremity of the crank there is fitted a iron from iron hooks long enough to reach the breakers; they are then put into the breakers so as to form a joint. thereby turning the eccentric the breakers pass by each other in an opposite direction and thus the machine is put in motion. This machine may be built of pine or hard wood at pleasure. What I claim as my invention and not previously known in the above described machine is the fitting the breakers together; the eccentric iron is in the pieces, and the hanging the breakers over the cross by which means they are made to touch the inside of the box at the bottom and top on each side.
